US00D944392S

(12) United States Design Patent (10) Patent No.: US D944,392 S
(45) Date of Patent: * Feb. 22, 2022

(54) DAILY PANTY LINER

(71) Applicant: PRODUCTOS FAMILIA S.A.,
Medellín (CO)

(72) Inventors: Lorena Cespedes Aislant, Medellín
(CO); Fabio Alberto López Pimienta,
Medellín (CO)

(73) Assignee: Productos Familia S.A., Medellín (CO)

() Term: 15 Years

(21) Appl. No.: 29/744,413

(22) Filed: Jul. 29, 2020

(30) Foreign Application Priority Data

Feb. 5, 2020 (CO) NC2020/0001272

(51) LOC (13) Cl. 24-04
